(57) **CLAIM**

The ornamental design for a charging device, as shown and described.

DESCRIPTION

FIG. 1 is a front isometric view of a charging device showing our design;

FIG. 2 is a back isometric view thereof;

FIG. 3 is a front view thereof;

FIG. 4 is a back view thereof;

FIG. 5 is a right side view thereof, the left side view being a mirror image thereof;

FIG. 6 is a top view thereof;

FIG. 7 is a bottom view thereof;

FIG. 8 is a front perspective view thereof, shown in an environment of use;

FIG. 9 is another front perspective view thereof, shown in a second environment of use; and,

FIG. 10 is another front perspective view thereof, shown in a third environment of use.

In FIGS. 1–10, the dash-dash broken lines illustrate portions of the charging device that form no part of the claimed design. The remaining dash-dash broken lines in FIGS. 8–10 illustrate environmental subject matter which forms no part of the claimed design. The dash-dot broken lines illustrate boundary lines that form no part of the claimed design.

The charging device is shown with a symbolic break in its length. The appearance of any portion of the charging device between the break lines forms no part of the claimed design. The break lines for no part of the claimed design.

1 Claim, 6 Drawing Sheets
